UNITED STATES PATENT OFFICE.

WILLIAM POUNTNEY, OF PORT JERVIS, NEW YORK.

DESIGN FOR A BOTTLE OR JUG.

SPECIFICATION forming part of Design No. 16,027, dated April 7, 1885.

Application filed February 7, 1885. Term of patent 7 years.

To all whom it may concern:

Be it known that I, WILLIAM POUNTNEY, of Port Jervis, in the county of Orange and State of New York, have invented and produced a new and original Design for Bottles or Hollow Ware, of which the following is a full, clear, and exact description.

Reference is to be had to the accompanying drawing, forming part of this specification, in which the figure is a side elevation of my new design for bottles or hollow ware.

The leading feature of my design consists of the circular frill-like configuration represented upon the margin of the circular body of the bottle or hollow ware, said configuration comprising spaced-apart bars and segments interposed between said bars. The bottle or hollow ware in this instance is in jug form, as shown, with a body of circular form, upon whose margin is represented a circular frill-like configuration comprising equally-spaced-apart bars *b*, and segments *b'*, interposed or inserted in the spaces between said bars. The bars *b* are each represented as being beveled from a central line to its sides upon its face, its outer ends also being shown as beveled from a central point to the sides. Within the ring *a*, bounding the

body of the bottle, the sides of said body are or may be represented ribbed or roughened and configurated, as shown at *a'*, the same consisting of a representation of a series of circularly-disposed arches with a centrally-arranged star.

Having thus fully described my invention, I claim as new and desire to secure by Letters Patent—

1. The design for a bottle or hollow ware, consisting of the circular frill-like configuration represented upon the margin of the circular body, said configuration comprising 40 spaced-apart bars with interposed segments, as shown and described.

2. The design for a bottle or hollow ware, consisting of the circular frill-like configuration represented upon the margin of the circular body, the sides of said body being represented with an annulus or ring, and with a series of circularly-arranged arches, centrally of which is disposed a star, as shown and described.

WILLIAM POUNTNEY.
